(57) **CLAIM**

The ornamental design for a motorcycle mirror, as shown and described.

DESCRIPTION

FIG. 1 shows a perspective view of a motorcycle mirror according to a first embodiment of the design in a non-operative position;

FIG. 2 shows a front view of the mirror of FIG. 1;

FIG. 3 shows a rear view of the mirror of FIG. 1;

FIG. 4 shows a left-side view of the mirror of FIG. 1;

FIG. 5 shows a right-side view of the mirror of FIG. 1;

FIG. 6 shows a top view of the mirror of FIG. 1;

FIG. 7 shows a bottom view of the mirror of FIG. 1;

FIG. 8 shows a perspective view of the motorcycle mirror of FIG. 1 in the operative position;

FIG. 9 shows a front view of the mirror in the operative position of FIG. 8;

FIG. 10 shows a rear view of the mirror in the operative position of FIG. 8;

FIG. 11 shows a left-side view of the mirror in the operative position of FIG. 8;

FIG. 12 shows a right-side view of the mirror in the operative position of FIG. 8;

FIG. 13 shows a top view of the mirror in the operative position of FIG. 8; and,

FIG. 14 shows a bottom view of the mirror in the operative position of FIG. 8.

In FIGS. 57-70, the parts shown in dotted lines do not form part of the claimed design.
